ing Corporation, a corporation of Delaware

Application December 19, 1929, Serial No. 415,226.
Renewed October 18, 1934. In France March
8, 1929

4 Claims. (Cl. 58—77)

The present invention relates to improvements in instruments such as stop watches, whereby their several parts will be made more substantial and their number reduced, thus simplifying 5 the functioning of these instruments.

The invention has further for its object to facilitate the dismounting of such instruments.

An instrument such as a time-piece or stop 10 watch whereby the above mentioned results are attained is specified in the following description.

In the accompanying drawings which show a preferred embodiment of the invention:

Fig. 1 is a plan view showing the several parts of a time-piece, only the supports of the other 15 movable parts being indicated.

Fig. 2 is a section of the same on a larger scale on the line 2—2 of Fig. 1.

The said time-piece is constructed in the following manner.

20 In the bored shaft of the seconds pinion 11 disposed at the center of the clockwork is mounted a long rod 12 pivoted at each end. The lower end turns in a bearing 18 and carries the hand 12' of the timepiece. The upper end turns in the cross piece of the timepiece. The bearing part at the end of the rod is not in contact with the said cross-piece, so that the said rod can move axially 25 with reference to the seconds pinion 11, the play being limited by a pressure spring 16.

30 The lower pivoting end of the pinion 11 rotates in the plate 26; the upper pivoting end traverses a special supporting cross-piece 24, and it carries on its outer end a cup-shaped member 17 whose interior has the form of a striated parabo- 35 loid comprising very numerous fine lines, as indicated at 17'.

The long rod 12 carries a cylinder or a tapered part 13 which is striated at 13' in the same manner as the said cup-shaped member and serves as 40 a driving pinion. Upon the rod 12 are also mounted two members to which is secured a disk 14 carrying a pin 14' which, when the apparatus starts, is adjacent the auxiliary wheel 19 of the apparatus, and, at each minute, the said pin 45 moves forward the wheels 19 and 20 by one tooth, due to the cross-member 21 holding the wheels except when moved by the pin. The wheel 20 carries the hand 20' of the apparatus, and also a first member 35 for the setting to zero. To the 50 aforesaid rod 12 is also secured a zero-setting member 15 which is rotatable with the said rod 12.

The engagement and release between the long rod 12 carrying the indicating hand of the time-piece, and of the seconds pinion 11 are effected 55 by the following mechanism.

A spring strip 8 is secured in the fixed position at one end; the other end being free, and having the shape of a fork, which end is engaged upon the said rod 12 and applies it against the disk 14. The said strip 8 has a step 8' and rests by means 5 of a bearing portion 8'' upon a bell-crank lever 7, urged by a spring 9, and actuated by a pivoting lever 6 comprising a projection 6' engaging a ratchet wheel (or lantern wheel) 4. The stroke of said bell-crank lever is limited by the stop 10. 10

The push-piece 30 of the timepiece actuates the large rocker arm 1 urged by a spring 2, and it rotates the said ratchet wheel 4 by means of the pawl 3.

The operation of the said apparatus is as follows:

1. To start the apparatus, the push-piece 30 is lowered, thus turning the said rocker arm 1 which acts by means of its pawl 3 to rotate the ratchet wheel 4. 20

When rotating, one of the pins of the ratchet wheel 4 meets and drives back the said projection 6' of the said lever 6 whose end is in contact with the said bell-crank lever 7. The end of this latter will thus allow the descent of the said strip 25 8 which constantly bears upon the same, and which moves from the step 8' and proceeds upon the bearing portion 8'' (Fig. 2).

The said spring strip 8 thus releases the disk 30 14, and the pinion 13 makes contact with the said member 17, so that the rod 12 rotates together 35 with the pinion 11, the pressure of the pinion 13 upon the said member 17 being assured by the spring 16.

2. To stop the apparatus, the said push-piece 35 30 is actuated, and this, through the medium of the arm 1, the spring 2, the pawl 3, turns the said ratchet wheel 4. The projection 6' thus passes between two pins of the wheel.

The lever 7, pivoting by the action of the spring 40 9, returns in the direction of the arrow (Fig. 2) from 8'' to 8' and raises the releasing spring 8. The forked end of said spring raises the disk 14 together with the device 12—13, whereby the release is effected, since the pinion 13 is no longer 45 engaged with the member 17, and the pin 14' is out of the plane of the wheel 19.

3. To set the apparatus to zero, the push-piece 30 is actuated, and this latter, through the said ratchet wheel 4, releases the arm 22 which under 50 the action of the spring 23 presses by means of its two pointed ends 40—41 upon the disks situated at the center and on the shaft of the meter, so that the two hands will be returned to zero. The lifting action of spring 8, as described in the pre- 55

ceding paragraph, also raises member 15 and brings it into the plane of arm 22, so that actuation of arm 22 will cause end 41 thereof to force member 15 and hence rod 12 and the timepiece 5 hand back to a zero position.

The invention further covers the special disposition of the winding mechanism which is mounted at the side of the dial either above or below the main plate, in such manner as to entirely disengage the support of the spring barrel, which carries a great number of the parts of the timepiece, and in this manner the apparatus can be readily taken apart for changing a spring or for cleaning, since the support of the said barrel 10 can in fact be removed without interfering with the parts which cover it.

What is claimed is:

1. In apparatus of the class described, a seconds pinion having a hollow shaft, driving means associated with said pinion, a rod passing freely 20 through the interior of said hollow shaft, an indicating hand carried by said rod, a cup-shaped member rigidly attached to said hollow shaft, and having its inner surface finely striated, a disk rigidly attached to said rod and having its lower edge finely striated, means tending to urge said disk into said cup-shaped member, a lever adapted to release said disk from contact with said cup-shaped member, means controlling the movements of said lever, and an actuating element 25 engaging said controlling means whereby the indicating hand may be successively set in motion or stopped.

2. In apparatus of the class described, a seconds pinion having a hollow shaft, driving means associated with said pinion, a rod passing freely 30 through the interior of said hollow shaft, a hand carried by said rod, a cup-shaped member rigidly attached to said hollow shaft, a disk rigidly attached to said rod, means tending to urge 35 said disk into said cup-shaped member, a second disk secured to said rod, a stud mounted on said second disk, a wheel adapted to be engaged by said stud, means including another hand adapt-

ed to be driven by said wheel, and a lever adapted to release said disk from said cup-shaped member and to simultaneously disengage said stud from said wheel.

3. In apparatus of the class described, a seconds pinion having a hollow shaft, driving means associated with said pinion, a rod passing freely 5 through the interior of said hollow shaft and carrying a time indicator, a cup-shaped member rigidly attached to said hollow shaft and having its inner surface finely striated, a disk rigidly attached to said rod and having its lower edge finely striated, means tending to urge said disk into said cup-shaped member, a second disk 10 attached to said rod, a stud mounted on said second disk, a wheel adapted to be engaged by said stud, another indicator, the said wheel being adapted to actuate said other indicator, and a lever adapted to release said first disk from said cup-shaped member and to simultaneously disengage said stud 15 from the said wheel.

4. In an instrument used as a timepiece, a driven seconds pinion, a hand-carrying shaft wholly free of any connection with and movable axially with respect to the seconds pinion, coupling means for connecting and disconnecting the pinion and shaft for movement of the shaft under the influence of the pinion, said means including a concaved member connected to the pinion and a cooperating plain member connected to the shaft, the cooperating surfaces of the concaved member and of the plain member being striated, an element guided by the shaft and movable longitudinally of the shaft for controlling the connection and disconnection of the coupling means, 25 a member cooperating with the element to force the element to a position to disconnect the coupling means or to permit the element to move to a position to permit connection of the coupling means, and a manual control mechanism for governing movement of the member in its relation to the element.

EDMOND ELIAS ULMANN.
